Inventor:
James Balmer

United States Patent Office.

JAMES BALMER, OF BROOKLYN, NEW YORK, ASSIGNOR TO HIMSELF AND
WILLIAM GREENLEAF, OF SAME PLACE.

Letters Patent No. 78,354, dated May 26, 1868.

IMPROVEMENT IN SELF-CLINCHING SPIKES.

The Schedule referred to in these Letters Patent and making part of the same.

TO ALL WHOM IT MAY CONCERN:

Be it known that I, JAMES BALMER, of the city of Brooklyn, in the county of Kings, and State of New York, have invented a new and useful Improvement in Self-Clinching Spikes; and I do hereby declare the following to be a full, clear, and exact description of the same, reference being had to the annexed drawings, making a part of this specification, in which—

Figure 1 is a side view of the spike.

Figure 2 is a perspective view.

Figure 3 is a view of one side at right angles to fig. 1.

Figure 4 is a view representing the practical application of the spike, and showing it in a clinched condition. Similar letters of reference indicate corresponding parts in all the figures.

This invention consists in a spike having its lower or pointed portion split or divided longitudinally into two parts or prongs, which are so bevelled that when the spike is driven into the wood they will be caused to diverge or spread apart in opposite directions parallel with the split or division, and thus clinch or secure the spike.

To enable those skilled in the art to understand the nature and construction of my invention, I will proceed to describe it with reference to the drawings.

The head A, and upper portion, B, of the spike, are of the ordinary shape and construction, but the lower portion is divided longitudinally into two parts or prongs, C C. The lower extremity of each of these prongs C is bevelled to a point, as clearly represented at α in the drawings, on the sides which are transverse to the split or cleft e, the bevel α upon one prong sloping in a contrary direction to that upon the other prong in such a way that when the spike is driven into the wood the two oppositely inclined surfaces α will cause the points of their respective prongs to diverge or spread apart in planes parallel with the cleft e, by the resisting action upon the said surfaces of the wood, into which the spike is driven, thus clinching or securing the spike, as shown in fig. 4. A split spike, of this construction, secures itself more firmly in the wood than one which spreads transversely to the split or cleft, as the split portions, diverging in the direction of their greatest thickness, require a greater force to withdraw them.

What I claim as my invention, and desire to secure by Letters Patent, is—

A spike split or divided longitudinally, and having its split parts so bevelled or inclined that when driven into the wood, the portions on opposite sides of the split or cleft will diverge in opposite directions parallel with the split or cleft, substantially as herein described.
